UNITED STATES PATENT OFFICE.

JESSE C. MARTIN, JR., OF SAUSALITO, CALIFORNIA.

LOCOMOTIVE-BOILER FURNACE.

1,316,628.

Specification of Letters Patent. Patented Sept. 23, 1919.

Application filed January 31, 1919. Serial No. 274,585.

To all whom it may concern:

Be it known that I, JESSE C. MARTIN, Jr., of Sausalito, in the county of Marin, State of California, have invented certain new 5 and useful Improvements in Locomotive-Boiler Furnaces, of which the following is a specification.

The hereinafter described invention relates to that class of open bottom refractory 10 lined locomotive type fire boxes wherein the fuel is ejected through a burner at the front end thereof and wherein the combustion chamber is provided by the fire box proper and the closure supported from the mud ring 15 thereof.

The object of the invention is to provide means directly secured to the mud ring of an open bottom refractory lined locomotive type fire box combustion chamber for supporting the rear end refractory wall thereof so as to provide an air passage into the combustion chamber between the refractory wall and the rear end of the fire box and to maintain such wall in position entirely independent of supports secured to the sheets of the fire box thereby eliminating the necessity of cutting and tapping holes with steam tight threads into the fire box sheets for studs to support the said wall, which with 25 its weight and vibration of service causes frequent breakage of studs resulting in boiler failures, and hazard to enginemen as well as deterioration of the boiler sheets from renewed tapping of larger holes for 30 studs to replace the broken ones.

Another object of the invention is to provide more substantial means than studs tapped into fire box sheets for maintaining the heavy refractory end wall away from 40 the rear end of the fire box on the wide type fire box boilers now in common use, the successful use of the said wall in wide type fire boxes depending upon the reliability of its support to withstand the increased exact- 45 ments, stresses or burdens of load and vibration placed thereon.

A further object of the invention is to eliminate the necessity of fire box inspection as required when the rear end refractory 50 wall is supported by studs tapped in fire box sheets; the inaccessibility of such studs often calling for the removal of adjoining refractory linings as well as the refractory end wall itself with consequent expense of time 55 and material.

To understand the invention reference

should be made to the accompanying drawings wherein, Figure 1 shows a vertical longitudinal section of an open bottom refractory lined locomotive type fire box and pan 60 forming therewith the combustion chamber, the pan provided with refractory end wall supporting means in accordance with my invention. Fig. 2 is a transverse section on line 2-2 Fig. 1 showing the rear end view 65 of the supporting means whereby the refractory end wall is maintained in place.

In the drawings numeral 1 is used to designate a refractory lined locomotive type fire box boiler, and 2 the pan or closure attached by studs to the mud ring 3 of the fire box, the fire box and pan together forming the combustion chamber 4. The fuel is injected into the combustion chamber through a burner 5, located at the front end 70 thereof, toward the refractory end wall 6. The refractory wall 6 is shown set out from the rear end of the fire box and in the present adaptation of my invention against the plate 7, being preferably inclined. The 75 plate 7 is substantially fixed by angle irons 8 and bracing members 9 to the pan 2 being entirely free of any direct attachment to the fire box sheets. Air is supplied into the combustion chamber 4 between the rear of 80 the fire box and the refractory wall 6 through a communicating draft opening 10 at the end of the pan 2. The entire load of the refractory end wall 6 as shown is carried in the pan 2, which being attached 90 to the mud ring 3 communicates the load of the said wall directly to the mud ring of the fire box.

In the use of the invention I do not restrict myself to the exact form of pan and 95 supports as shown, it being within the scope of the invention to provide any means normally located at the lower portion of the fire box for supporting the refractory wall out of contact with the rear end of the fire box 100 from the mud ring thereof.

In practical service it is possible to maintain the refractory end wall as I support it from the mud ring of the fire box combustion chamber at minimum cost and in accordance with locomotive boiler rules and regulations, performing in a practical and efficient manner its true function of introducing air into the combustion chamber between the rear of the fire box and the wall 110 as set out therefrom through the draft opening (10) at substantially the full width of the

fire box and while the combustible gases are at the farthest point from the flues, which is highly desirable, this being of particular importance in the wider type locomotive 5 fire boxes which without this full width of air distribution into the combustible gases fail to receive the requisite amount of oxygen necessary in the rear corners of the fire box, and as a result only partial oxidation of the combustible gases takes place with consequent fuel loss and depositing of objectionable carbon in the flues of the boiler.

What I claim is:—

In a locomotive type fire box wherein the

fuel is injected through a burner at the 15 front end thereof and wherein a refractory end wall is set out from the rear end of the fire box opposite the fuel delivery of means for supporting the said refractory wall by the mud ring of the fire box.

In testimony whereof I have signed my name to this specification in the presence of two subscribing witnesses.

JESSE C. MARTIN, JR.
